Primary Examiner — Rhea M Shields*(74) Attorney, Agent, or Firm* — George H. Leal(57) **CLAIM**

The ornamental design for a feminine hygiene article package, as shown and described.

DESCRIPTION

FIG. 1 is a front perspective view of a first embodiment of a feminine hygiene article package embodying the new design;

FIG. 2 is a front view of the design shown in FIG. 1;

FIG. 3 is a back view of the design shown in FIG. 1;

FIG. 4 is a top view of the design shown in FIG. 1; the bottom view is the same and thus omitted; and,

FIG. 5 is a right side view of the design shown in FIG. 1; the left side view is the same and thus omitted. The figures are lined for transparency.

In the drawings, the broken lines are for the purpose of illustrating environment only and form no part of the claimed design.
